UNITED STATES PATENT OFFICE.

HENRY V. H. SMITH, OF NORFOLK, VIRGINIA, ASSIGNOR TO TOMPKINS BROTHERS, OF TROY, NEW YORK.

BUR-HOLDER ATTACHMENT FOR KNITTING-MACHINES.

SPECIFICATION forming part of Letters Patent No. 609,594, dated August 23, 1898.

Application filed July 23, 1897. Serial No. 645,753. (No model.)

To all whom it may concern:

Be it known that I, HENRY V. H. SMITH, of the city of Norfolk, county of Norfolk, State of Virginia, have invented new and useful Improvements in Bur-Holder Attachments for Knitting-Machines, of which the following is a specification.

My invention relates to that class of devices which are used to position and relatively adjust the sinker-burs of knitting-machines to the needles of the latter, and more particularly to a mechanism for delicately adjusting the sinker-burs, so as to give any desired pitch to the latter which may be required.

Accompanying this specification to form a part of it there are two plates of drawings containing five figures illustrating the application of my invention, with the same designation of parts by letter reference used in all of them.

Of the illustrations, Figure 1 is a perspective of a knitting-machine bur-holder standard, to which my invention is shown as applied. Fig. 2 is a central vertical section of the apparatus shown at Fig. 1, illustrating a part of the machine-table. Fig. 3 is a section taken on the line $x' x'$ of Fig. 2. Fig. 4 is a side elevation of a gear-wheel having a grooved perimeter and which is mounted upon a sleeve provided with trunnion-form journals, which when in position for use in the machine is mounted upon and secured to the bur-holder bar. Fig. 5 is a side elevation of the gear-wheel which is shown at Fig. 4 and the shaft having a worm-gear formed thereon and arranged to mesh into the perimetral teeth of said wheel to rotate it.

The several parts of the apparatus thus illustrated are designated by letter reference, and the function of the parts is described as follows:

The letter T designates the machine-table, and S' the bur-holder standard, attached to and upwardly projected from the machine-table.

The letter B designates a bracket which attaches adjustably to the outer side of the standard in offset projection by means of a slot S^2 , vertically formed in the standard, a bolt b^2 having a head h' to straddle the sides

of the slot in the standard, and a retaining-nut n , which is threaded onto said bolt where it is in passing through the bracket extended beyond the latter at l . This bracket B has offset from its outer side the horizontally-extended arm A, which is of a tubular form and is recessed at a^2 to receive the worm-actuated wheel W and is provided with bearings for the worm-gear shaft to journal in at a^4 .

The letter K designates a cap which is threaded onto the outer end of the bur-holder bar b^3 , and the letter M designates a head which is made with a neck m^2 , adapted to enter the tube-form area a^6 of the arm A at its outer end, and is provided with an encircling collar N, which when the neck of the head is entered within the interior area a^6 of the arm A will abut against the outer end of the latter at n^4 .

The letter C designates a grip-nut which is threaded onto the bar b^3 and arranged between the cap K and the head M, by means of which when the nut is turned on its threaded connection with the bar b^3 the latter may be moved outwardly or inwardly to position the sinker-bur relatively to the needles as to horizontal adjustment with the cap K, turned to hold the grip-nut and keep the parts in position as thus adjusted.

The letter t^2 designates a set-screw which is threaded into a stop-collar I, arranged to project outwardly through a slot S^3 , opening out through the bottom of the tubular area a^6 . This set-screw is provided with a head t^3 , adapted to straddle the slot in which it is placed and to hold the collar I in a desired position to regulate the resilient action of the spring O, arranged in the tube-form area a^6 to encircle the bar b^3 between the stop I and the collar d, also arranged in the interior area a^6 and fast upon bar b^3 .

The letter L designates another set-screw, which is threaded into the arm A, and when screwed inwardly is adapted to engage with the neck of the head M (indicated at m^2) to hold the head in place.

The wheel W has its gear-teeth preferably formed in a groove circumferentially made in the perimeter of the wheel, and the latter is provided with trunnion-form journals J J, one of which turns in the inner end of the

area a^6 and the other in the recess a^2 . This wheel W is loosely keyed to the bar b^3 and when actuated to turn also operates the bar b^3 to turn.

5 The letter a^5 designates a shaft which is horizontally arranged to journal in the bracket B at $a^4 a^4$, and this shaft is provided with a worm-gear G, adapted to mesh into the perimetal teeth of the wheel W, and when this 10 shaft is turned it actuates the latter and the bur-holder bar b^3 to turn with a slowly-actuated and delicate movement.

The letter F designates the bur-holder proper, which is secured to the inner end of 15 the bar b^3 at f^2 and therefrom is projected downwardly and laterally on an angle to produce the shelf f^3 , into the upper surface of which the sinker-bur B³ journals vertically.

As thus constructed, when it is desired to 20 operate the bar b^3 to move inwardly, so as to bring the sinker-bur blades farther inward between the needles, the cap K is screwed outwardly and the grip-nut C is turned on its threaded connection with the bar b^3 to move 25 that end of the latter to which it is attached and the bur-holder proper toward the needles until the desired position horizontally of the sinker-bur to the needles is reached, and when this has been done the spring-stop set- 30 screw t^2 is operated to regulate the tension of the spring O upon the bar b^3 , and the cap K is then screwed up onto the bar b^3 to abut against the grip-nut C to hold the latter in position as adjusted. To move the bur-holder 35 bar b^3 outwardly, the cap K is screwed outwardly, as before, and the grip-nut is reversed as to movement until the sinker-bur is moved to the desired position, when the spring-tension is again regulated and the cap K screwed 40 onto the bar b^3 to abut against the grip-nut as before. The parts thus described in their operation constitute the horizontal adjustment of the sinker-bur to the needles.

When it is desired to change the pitch of

the bur-blades relatively to the needles, a 45 wrench is applied to the square head h^2 of the worm-shaft a^5 , by the rotation of which the worm thereon operates the worm-wheel W, that is keyed to the bar b^3 , so as to move the latter with a slow and limited measure of rotation and which as rotated will cause the sinker-bur blades to incline from a perpendicular relatively to the needles more or less, as may be desired. This inclination of the sinker-bur enables the operator of the machine to relatively position the pitch of the bur-blades to the needles with a varied adjustment to adapt to the use of differing yarns and their delivery to the needles. 50 55

Having thus described my invention, what 60 I claim, and desire to secure by Letters Patent, is—

The combination with a standard upwardly projected from a knitting-machine table, said standard being provided with a laterally-extended tube-form arm, and having a bracket projected therefrom; of a bur-holder bar provided with a shelf on its inner end, and adapted to turn in said tube-form arm; a sinker-bur journaled on said shelf; a worm-wheel 65 mounted on said bur-holder bar and arranged in a recess formed in said standard-bracket; a shaft provided with bearings in said bracket and having mounted upon it a worm adapted to mesh into said worm-wheel, whereby as 70 75 said worm-shaft is rotated, the bur-holder may be rotated with small measures of movement and thus cause the sinker-bur to incline more or less from a perpendicular and thus give to the bur-blades a regulated measure of 80 pitch substantially as shown and described.

Signed at Norfolk, Virginia, this 13th day of February, 1897, in the presence of the two witnesses whose names are hereto written.

HENRY V. H. SMITH.
